SUPPORT RACK FOR COOKING UTENSIL
LIDS OR THE LIKE

Roger Edouard Guillaumant, 813 Mound St.,
Valparaiso, Ind.

Filed Oct. 24, 1960, Ser. No. 62,597

Term of patent 14 years

(Cl. D44—29)

FIGURE 1 is a top perspective view of a support rack for cooking utensil lids or the like embodying my design; and

I claim:

The ornamental design for a support rack for cooking utensil lids or the like, as shown.
